UNITED STATES PATENT OFFICE.

WILLIAM W. WATSON, OF JAMESTOWN, NEW YORK.

SHEET-METAL WINDOW-SCREEN FOR RAILWAY-CARS.

1,238,854.

Specification of Letters Patent. Patented Sept. 4, 1917.

Application filed March 26, 1917. Serial No. 157,358.

To all whom it may concern:

Be it known that I, WILLIAM W. WATSON, a citizen of the United States, residing at the city of Jamestown, in the county of 5 Chautauqua and State of New York, have invented certain new and useful Improvements in Sheet-Metal Window-Screens for Railway-Cars, of which the following, taken in connection with the accompanying drawings, is a specification.

The invention relates to sheet metal window screens for railway cars and similar uses and is an improvement upon the window screen construction shown in Letters 15 Patent Nos. 836,475 and 956,239; and the object of the improvement is to provide a tubular screen frame with inner and outer corner braces which greatly strengthen the corners of the screen frame, and to provide 20 other improvements and conveniences, as shown in this specification and the accompanying drawings and pointed out in the claims.

In the drawings, Figure 1 is a plan view 25 of the screen frame with the improved construction, parts of the screen frame being shown in section. Fig. 2 is a sectional view of the combined corner brace and spring bolt holder at line X—X in Fig. 4 showing 30 the construction and arrangement of the parts with the spring bolt in the barrel of the holder; and Fig. 3 is a top plan view of the corner brace and bolt barrel; and Fig. 4 is an end elevation of the same showing 35 the end of the bolt barrel with the bolt stem therein; and Fig. 5 is a plan view of the flat pattern for the combination corner brace and bolt barrel before it is shaped in the angular tubular form by the forming 40 dies. Fig. 6 is an elevation of one of the upper corners of the frame; and Fig. 7 is an elevation of one of the lower corners of the frame, showing the construction of the same; and Fig. 8 is a perspective view of 45 one of the upper corners of the screen showing the grooved edge and bolt therein with one of the side lugs which holds the screen upon the slide, the frame side being shown in sectional perspective. Fig. 9 is a perspective view of a portion of the opposite 50 lateral sides of the screen frame showing one of the holding springs in the deep groove therein. Fig. 10 is a perspective view of a portion of the lower side of the 55 screen frame with the screen wire therein

and showing the downwardly projecting weather strip. Fig. 11 is a detail perspective view of the channel-piece with the cross-wise bar or roll turned therein for engagement by a hook in order to pull down the window screen, which channel piece forms a reinforcement for the central portion of the lower screen side, as shown in Fig. 1. Fig. 12 is a perspective view of one of the tubular sheet metal corner braces for the 60 lower screen corners wherein the spring bolts are not used; and Fig. 13 is a plan view of the flat pattern for forming the corner brace shown in Fig. 12. Fig. 14 is an edgewise elevation of a portion of the 70 grooved edge of the lateral frame side showing one of the lugs or holding plates attached to the edge of said screen side. Fig. 15 is a perspective view of a portion of one of the upper screen sides showing the construction and arrangement for the operating 75 lever for the spring bolt, the opening for joining the operating lever to the bolt stem and the plate for closing said opening being shown, as well as the covered opening 80 in the groove and flange for the insertion of the operating lever; Fig. 16 is a sectional view of the frame side at line Y—Y in Fig. 15 showing the lever inserted therein and the openings on the opposite sides. Fig. 17 85 is a perspective view of a portion of one of the frame sides showing the sunken hand grip therein and the guide lug on the side thereof.

Like characters of reference refer to corresponding parts in the several views.

The numeral 10 designates the tubular sheet metal frame side which is cut and bent from the flat sheet metal strip by means of suitable dies so as to form the lengthwise 95 groove 11 along the inner edges of the frame side.

The numeral 12 designates the top rail which is preferably formed of one or more strips of sheet metal shaped so as to form 100 a lengthwise groove 11 which opens sidewise along the inner edge and a lengthwise groove 13 which also opens sidewise along the outer edge, both of said grooves enlarging inwardly. The inner groove 11 enlarges inwardly to receive the spline or holding strip 14 for attaching the screen fabric 15 within the groove 11. The outer groove 13 enlarges inwardly to receive therein the weather stripping 16 which fits 110

within the groove 13 and extends beyond the side of the frame side.

The top rail or upper tubular frame side 12 is preferably formed of two sheet metal strips 17 and 18, the two lengthwise contacting edge portions of which are pressed together and bent into the lengthwise channel groove along each of the edges, both of the edges of the sheet 18 being left short and 10 both edges of the sheet 17 on the outer side extending over the edges of the sheet 18 into each of the grooves 11 and 13, thereby narrowing the mouths of each of the grooves 11 and 13 the thickness of the inturned sheet 15 metal edges so that said grooves may be said to enlarge inwardly to hold the spline 14 and the weather stripping 16. The contacting edges of the plates 17 and 18 are preferably welded or soldered or otherwise attached together so that they cannot turn or 20 move upon one another.

The lower cross rail or tubular frame side 19 is preferably made of two sheet metal strips 20 and 21 in somewhat the same form 25 as the upper frame side or cross rail 12, the exceptions being that the groove 11 is made slightly different, the strip 21 being bent at an inclined angle 22 to prevent the use of hooked instruments upon the screen or frame 30 side in lowering the same as is necessary in car screens, and the lengthwise groove 23 for the weather strip 16 is preferably formed on the outer side of the lower edge of the rail 19 so that said groove opens downward 35 and said weather strip 16 may be pressed downward onto the window sill.

The corners of the screen frame are preferably mitered and united by soldering or 40 welding though they may be united by any other suitable means, for example, sweating, riveting or screwing. The inner corners of the frame sides are braced by extending the ends of the folded inner flanges 24 so that 45 the extensions of said flanges 24 interlap one another, as shown at 25, the flanges 24 being bent sufficiently to accommodate one another and the interlapped ends are soldered or welded together so as to firmly hold and 50 brace one another, thereby making an exceedingly strong attachment for the inner corners of the frame sides. On account of the inclined or beveled inner edge 22 of the lower cross rail, the folded end of the flange 55 24 is lapped within said edge 22 and attached thereto thereby strengthening the lower corners of the frame.

The opposite corners, preferably of the upper frame side, are provided with the 60 spring bolts 26, and the opposite outer edges of the lateral frame sides have the grooves 27 and 28 therein for slidably mounting upon sliding ways on the window frame. The shallower groove 27 is provided with 65 the lugs 29 on their outer edge to assist in

holding the grooved edge upon the sliding way, and the deeper groove 28 has the springs 30 therein for holding the grooved edges upon the sliding ways and making it possible to insert the screen frame upon the sliding ways, a handhold 31 being provided on the shallower grooved edge of the frame side by soldering or otherwise attaching a strip of metal around the opening in the hollow frame side for the hand-hold 31, as 70 75 shown in Fig. 17, thereby making a convenient sunken hand-grip in the frame side which is strong and durable and which does not permit moisture to enter the frame side.

It is apparent that the mitered ends of the 80 hollow sheet metal frame sides must be strongly attached to one another. For this purpose I prefer a simple interior sheet metal tubular corner brace 32 for those corners in which there are no spring bolts and 85 33 for the corners in which a spring bolt is inserted.

The tubular corner braces 32 and 33 are made from the flat sheet metal in the following manner: The corner brace 33 which holds the spring bolt 26 is a combination corner brace and bolt barrel, having the bolt barrel 34 in one of its angular portions. In the flat sheet metal blank as shown in Fig. 5, the central portion 35 is formed into the tubular barrel 34 for the spring bolt 26 and has the outwardly extending edges 38 which brace against the inner wall of the frame side. The two wings 36 and 37 are extended 90 95 out from one end of the central portion 35 in the sheet metal blank, the wing 37 being sufficiently larger than the wing 36 so that when formed in the channel shape and into the tubular form the wing 36 shuts into the wing 37, suitable cuts being made adjacent the portion 35 to permit of the folding of the wings 36 and 37.

The end 39 of the barrel 34 is closed sufficiently to hold one end of the spring 40 around the stem 41 of the bolt 26, so that 100 105 said coil spring 40 works freely around the stem 41 within the barrel 34. The inner end of the stem 41 is attached to the lever 42 which lever is pivotally mounted in the frame sides so as to withdraw the bolts 26 by pressing the levers 42, thus forming a 110 115 convenient spring bolt for each of the upper corners which support and lock the screen frame firmly in position upon the sliding ways.

In order that the lever 42 may extend within the sheet metal frame side, said lever must extend through the groove 11 on the inner edge of the tubular frame side. Accordingly a tube 43 is provided in the bottom of the groove 11 which enlarges inwardly to permit the required pivotal action of the lever 42 in operating the bolt 26, and a hole 57 is provided through the flange 24 120 125 130

opposite the end of the tube 43 so that the operating lever 42 may be inserted and pivotally attached within the frame side. In order to attain the pivotal attachment of 5 the stem 41 to the inner end of the operating lever 42, a countersunk opening 44 is provided in the frame side on both sides of said inner end of the lever 42 and plates 45 are soldered into the counter sunk opening 44 10 so that after being so soldered they may be polished and finished with the remainder of the frame side, yet providing a means by which the joint between the inner end of the stem 41 and lever 42 is easily accessible, 15 it only being necessary to unsolder the plate 45 and remove the same.

For the lower corners or corners where the spring bolts 26 are not needed, the simple tubular corner brace 42 is provided 20 which is made as shown in Figs. 12 and 13, a central portion 46 folding into one of the angular tubular portions and the wings 47 and 48 folding into the other, much the same as in corner brace 33. The notches 49 25 and 50 are provided to form the drip hole 51 in the lower side so that should moisture enter the frame side it will drip out through the drip hole 51, a drainage opening 52 being provided in the lower cross rail opposite 30 the drip hole 51 so that the water may drain out of the frame side through the holes 51 and 52.

As hereinbefore stated, the edge 22 of the lower frame side is preferably formed with 35 an incline or bevel, as shown in Fig. 10, to prevent injury to the sheet metal frame side by the use of a hook in drawing down or pushing up the screen within the car side. In order to provide for the correct usage of 40 the hook, upon the frame side, a short channel strip 53 is attached within the lower sheet metal tubular frame side 19, being welded or soldered or otherwise attached therein and the bottom of the channel strip 45 53 is slotted at 55 each side of its central portion and the cutaway parts are bent over one another so as to form a strong crosswise 50 roll 54 to receive the hook 56 through the openings 55, as shown in dotted outline in Fig. 1. The sheet metal frame side 19 is correspondingly slotted so as to register with the slot 55 and the sheet metal cutaway portion for said slot is also not severed at the opposite inner sides, the same as in slots 55, 55 said sheet metal portions being bent over one another in the crosswise metal roll 54, thereby forming a strong crosswise bar or roll of the intercurved metal from the slots 55, said slots forming openings through 60 which the hook 56 can be easily inserted in order to engage the roll 54 and draw down the screen frame. The channel strip 53 is placed midway of the length of the lower tubular frame side so that the hook 56 draws 65 true on said frame.

I claim as new:—

1. In a window screen, a sheet metal frame comprising tubular side and end pieces, said side and end pieces mitered at the corners and attached to one another, extensions on 70 said side and end pieces at the inner corners to interlappingly attach them to one another and brace said inner corners, screen wire, and means for attaching said screen wire to said frame.

2. In a window screen, a sheet metal frame with tubular side and end pieces having a groove along their inner edges, extensions of 75 said inner edges at each of the corners interlapped and welded to brace said corners, 80 screen wire, and a filling strip for attaching said screen wire in said groove.

3. In a window screen, a sheet metal frame comprising tubular side and end pieces, a flange along the inner edges of said 85 side and end pieces to form a groove, screen fabric, a filling strip for attaching said fabric in said groove, and interlapping extensions on the ends of said flanges welded to one another at each corner to brace and 90 strengthen the inner corners of said frame.

4. In a window screen, a sheet metal frame comprising tubular side and end pieces, a flange along the inner edges of said side and end pieces to form a groove, screen fabric, a filling strip for attaching said fabric in said groove, and an extension on one of said 95 flanges at each corner turned at an angle and welded to the end of the adjacent flanged end to strengthen and brace said corner.

5. In combination with a tubular frame corner, a corner brace comprising a T-shaped metal plate, the central portion of said T-shaped metal plate folded in a tube and the wing portions interfolded in a tube at an 105 angle to said central portion, said tubes forming a corner brace and fitting within the ends of the adjacent tubular frame sides.

6. In a window screen, a sheet metal frame having tubular side and end pieces with mitered joints at the corners, an interior corner brace for each corner of said frame comprising an angular tube formed from a sheet metal plate, portions of said sheet metal plate being folded to fit within the adjacent 110 side and end pieces at each of said mitered corners, said mitered corners being soldered to said tubular corner braces.

7. In a window screen, a hollow tubular sheet metal frame, the lower frame side having a beveled upper edge to prevent hooking thereon, said lower frame side having spaced openings in the lower edge thereof, and a crosswise brace between said spaced openings to receive an operating hook over said 115 brace to draw down the screen.

8. In a window screen, a sheet metal frame having tubular frame sides, the lower tubular frame side having an opening therein, and a crosswise brace in said lower frame 120

125

side adjacent said opening to receive an operating hook over said brace to draw down the screen.

9. In a window screen, a sheet metal frame having tubular frame sides, a channel strip within the lower tubular frame side, partially cutaway strips cut from said channel strip and the adjacent frame side interfolded to form a crosswise brace having openings on each side thereof to receive an operating hook over said brace through said openings.

10. In a window screen, a sheet metal frame having a tubular bottom rail, said rail having strip-like parts displaced therefrom with one end attached to the rail, said strips being bent to interengage and provide a window-lowering hook engaging means, and the openings provided by the displacing of said strip-like parts receiving said hook therethrough.

11. In a window screen, a sheet metal frame comprising tubular side and end pieces, a hand-grip in the tubular frame comprising a lengthwise opening in the frame side, and a strip of metal soldered to the op-

posite inner sides of said sheet metal tubular frame side around said lengthwise opening to form an inclosed hand-grip the depth of the tubular frame.

12. In a window screen, a sheet metal frame having a tubular bottom rail, a part of said rail being displaced and shaped to form a means to engage a window lowering hook, and the opening provided by the displacing of said part receiving said hook therethrough.

13. In a window screen, a sheet metal screen covered frame having sides and ends connected at the corners thereof, the adjacent portions of the sides and ends having overlapping substantially right angular extensions, and means to secure said extensions to one another in superimposed relation to brace the corners of the frame.

In testimony whereof I have affixed my signature in the presence of two witnesses.

WILLIAM W. WATSON.
